US0D1020356S

(12) **United States Design Patent** (10) **Patent No.:** **US D1,020,356 S**
(45) **Date of Patent:** **** Apr. 2, 2024**

(54) **WOK**

(71) Applicant: **Weber-Stephen Products LLC**,
Palatine, IL (US)

(72) Inventors: **Robert Farmer**, Naperville, IL (US);
Cassandra A. S. McVey, Palatine, IL (US); **Brian C. Donnelly**, Naperville, IL (US); **Christian Hyde**, Schaumburg, IL (US); **Michelle Stohl**, Glenview, IL (US)

(73) Assignee: **Weber-Stephen Products LLC**,
Palatine, IL (US)

(**) Term: **15 Years**

(21) Appl. No.: **29/797,450**

(22) Filed: **Jun. 30, 2021**

(51) LOC (14) Cl. **07-02**

(57) **CLAIM**

The ornamental design for a wok, as shown and described.

DESCRIPTION

FIG. 1 is a perspective view of a wok.

FIG. 2 is a front view of the wok of FIG. 1.

FIG. 3 is a rear view of the wok of FIG. 1.

FIG. 4 is a right side view of the wok of FIG. 1.

FIG. 5 is a left side view of the wok of FIG. 1.

FIG. 6 is a top view of the wok of FIG. 1; and,

FIG. 7 is a bottom view of the wok of FIG. 1.

The dot dash broken line in FIG. 7 depicts a boundary line.

The broken line and the surface shown within the boundary line form no part of the claimed design.

1 Claim, 7 Drawing Sheets
